UNITED STATES PATENT OFFICE

ISAAC E. PALMER, OF MIDDLETOWN, CONNECTICUT, ASSIGNOR TO THE I. E. PALMER CO., OF MIDDLETOWN, CONNECTICUT, A CORPORATION OF CONNECTICUT.

ADJUSTABLE COUCH-HAMMOCK AND FRAME THEREFOR.

1,008,614.

Specification of Letters Patent. Patente 1 Nov. 14, 1911.

Application filed August 22, 1911. Serial No. 645,421.

To all whom it may concern:

Be it known that I, ISAAC E. PALMER, a citizen of the United States, and a resident of Middletown, in the county of Middlesex 5 and State of Connecticut, have invented an Improvement in Adjustable Couch-Hammocks and Frames Therefor, of which the following description, in connection with the accompanying drawings, is a specification, like characters on the drawings representing like parts.

This invention relates to adjustable couch hammocks and frames therefor.

In order that the principle of the invention may be readily understood, I have disclosed a single embodiment thereof in the accompanying drawing, wherein—

Figure 1 is a plan view of one form of frame constructed in accordance with my 20 invention; Fig. 2 is an end elevation thereof showing the frame in flat position; Fig. 3 is a similar view showing the frame with its back rest in angular position with respect thereto; Fig. 4 is a side elevation of a 25 couch hammock embodying my invention; Fig. 5 is an end elevation thereof; and Fig. 6 is an end elevation of a slightly modified form of my invention.

In my Patent No. 972,711, I have disclosed a couch hammock provided with a frame having a back rest angularly positionable with respect thereto. The said frame is therein supported upon transverse strips at the lower edges of the suspension 25 ends. The frame is adjustable transversely of the hammock, so that when the back rest is elevated the frame may be slid more or less transversely of the suspension ends, so as to place the frame and hammock structure in equilibrium.

In accordance with my present invention I have provided means whereby the equilibrium or poise of the hammock may be automatically obtained; that is to say, where- 45 by the angular adjustment of the back rest effects in and of itself the lateral shifting of the frame with respect to the suspension ends, and conversely whereby the lateral shifting of the frame may effect the desired 50 adjustment of the back rest.

Referring more particularly to the drawings, I have, in Figs. 4 and 5, represented suspension ends 1—1 of a couch hammock. Obviously any suitable suspension means 55 may be provided, whether the same consist

of cloth strips or chairs or other desired strand supports. Preferably, however, I provide fabric suspension ends having at their lower edges transverse strips 2 positioned in hems thereof.

The frame in accordance with the preferred embodiment of my invention is composed of side members 3—3 and end members each composed of pieces 4, 5 rigidly connected respectively to the side members 3 and respectively hinged together, as indicated at 6. The side member 3 and end pieces 4—4 constitute the back rest of the frame and hammock, it being evident that the hinges 6 may be positioned at any desired point between the side members of the frame and that if desired a plurality of hinges may be employed at each end, so that either side of the frame may be elevated to constitute a back rest. Moreover, the frame 75 may itself be rigid and may be provided with a supplemental or other back rest hinged thereto if desired, or otherwise suitably supported thereon for angular adjustment, as will be readily understood. Preferably, however, a portion of the frame 80 itself constitutes the back rest.

The frame is supported by the suspension ends, and in the present embodiment of the invention the end pieces 4, 5 are directly received upon the transverse strips 2, which may be wooden strips or metallic rods if desired or any other suitable material. I may connect the transverse strips and end pieces 4, 5 in any suitable manner, but preferably I employ screws 2, though if desired, I may employ hooks preferably permanently secured to the strips 2 and adapted detachably to engage the end pieces 4, 5, so as to permit the ready separation of the suspension ends 1—1 from the frame. Any suitable number of screws, hooks or other connecting means may be employed.

In order to provide a sliding engagement with the frame and the transverse strips 2, I have herein provided longitudinal slots 8 in the said transverse strips into which take bolts 9 upon the end pieces 5—5 of the frame. These bolts are provided with nuts 10—10 and are of the proper size to permit the desired sliding movement of the frame upon the strips. In accordance with my invention, I provide means for automatically effecting the lateral shifting of the frame or of the suspension ends or their transverse 110

strips upon or with angular adjustment of the back rest, and conversely, the angular adjustment of the back rest by the transverse shifting of the suspension ends of the frame; that is, when the back rest of the frame is at a proper angle to permit this to be effected. Preferably, I accomplish this result by providing an arm 11 at each end of the frame pivoted to the end pieces 4, at 10 12 and to the transverse strip at 13. These arms may be of any suitable material, but preferably are metallic and are secured in place by screws as indicated. Obviously movement of the back rest portion of the 15 frame from the position shown in Fig. 2 to that shown in Fig. 3, or to any other or intermediate position, automatically effects the transverse shifting of the suspension ends with respect to the frame, or vice versa, or 20 a combination of the two movements, and therefore establishes or preserves the equilibrium or poise of the hammock. Conversely, force applied to the flat portion of the 25 hammock to shift it transversely of the suspension ends will, when the angular position of the back rest is such as to permit this movement, change the angular position of the back rest portion thereof. That is to say, a relative shifting of the frame and of 30 the suspension ends takes place which establishes the equilibrium or poise of the hammock.

The weight of the parts and the friction incident to use preserve the parts in their 35 adjusted position, but if desired I may provide supplemental means to hold the back rest of whatever type employed in any adjusted position. For that purpose, I have in Figs. 2 and 3 shown arms 14 pivoted at 40 15 to the arms 11 and having notched ends 16 to engage screws or pins 17 upon a convenient portion of the hinged portion of the back rest as indicated. When the back rest has been brought into the desired angular 45 position, the arms 14 are engaged with the screws or pins 17, and thereby the back is locked or positively held in position. Obviously, by the use of interchangeable parts or by adjustments, or otherwise, the arms 50 14 may be made to hold the back rest in any one of a number of angular positions. Preferably I provide a suitable number of anti-friction rolls 18 in the end members of the frame to facilitate the transverse adjustment 55 of the parts.

In Fig. 6, I have shown a slightly modified form of my invention, wherein the end pieces 4, 5 of the frame have pivoted thereto at 19 arms 20 having hooked ends 21 adapted to engage angular or bayonet slots 22 in the arms 11, the construction being such that when the back rest is brought into angular position, the hooked ends of the arms 20 engage the angular portions of said slots 22, thereby positively to lock or hold the frame

in angular position. If desired, however, and as previously stated, I need not employ means positively to lock or hold the means in adjusted position, but may rely upon the weight and friction of the parts for this 70 purpose.

From the foregoing description, it will clearly be understood that the back rest is automatically brought into angular position from a horizontal position, or conversely 75 into a horizontal position from an angular position, or that the angular position may be varied automatically by relative shifting movement of the suspension ends and the frame.

Having thus described one illustrative embodiment of my invention, I desire it to be understood that although specific terms are employed, they are used in a generic and descriptive sense and not for purposes of limitation, the scope of the invention being set forth in the following claims.

1. A couch hammock comprising in combination flexible suspension means having transverse strips, a frame supported at its 90 ends by said transverse strips, said frame having a longitudinal member thereof angularly adjustable with respect to the remainder thereof, and connecting means between said strips and said frame for transversely 95 adjusting said frame by angular movement of said frame member.

2. A couch hammock comprising in combination flexible suspension means having suspension strips, a frame composed of side 100 members and divided, hinged, end members supported by said strips, and connections between said frame and strips for laterally shifting said frame by angular adjustment of one side member of the frame.

3. A couch hammock comprising in combination flexible suspension means having suspension strips, a frame composed of side members and divided, hinged, end members, supported by said strips, and means for 110 laterally shifting said frame by angular adjustment of a side member of said frame.

4. A couch hammock comprising in combination flexible suspension means having suspension strips, a frame composed of side 115 members and divided, hinged, end members supported by said strips, and arms connecting the hinged end members of the frame to said transverse strips.

5. A couch hammock comprising in combination suspension means, a frame supported by said suspension means and having a back rest adjustable at an angle with respect thereto, and means laterally to shift said frame with respect to said suspension 125 means upon angular changes in the position of said back rest.

6. A couch hammock or the like comprising, in combination, suspension means, a frame supported by said suspension means 130

and having a back rest adjustable at an angle with relation thereto, and means to shift the relative position of said frame and said suspension means, transversely of the hammock, upon angular changes in the position of said back rest.

7. A couch hammock comprising in combination cloth suspension ends having transverse strips at their lower edges, a skeleton frame supported by said strips, said frame having a back rest, and means to shift said frame laterally of said suspension ends by angular adjustment of said back rest.

8. A couch hammock or the like having a frame composed of side and end members, transverse strips having suspension means and by which said frame is supported, a plurality of sliding connections between each end member of the frame and said transverse strips, a back rest for said frame, and means for laterally shifting said frame by manipulation of said back rest.

9. A couch hammock or the like having

a frame composed of side and end members, 25 transverse strips having suspension means and by which said frame is supported, said frame having a back rest angularly adjustable with respect to the frame, and means to change the angular position of the back 30 rest by transverse shifting movement of said frame.

10. A couch hammock or the like comprising, in combination, suspension means having transverse strips, a frame supported 35 by said suspension means and having a hinged back rest adjustable at an angle with relation thereto, and members 11 connected to said back rest and to said transverse strips. 40

In testimony whereof, I have signed my name to this specification, in the presence of two subscribing witnesses.

ISAAC F. PALMER.
